(57) **CLAIM**

The ornamental design for a liquid and cup dispenser as shown and described.

DESCRIPTION

FIG. 1 is a perspective view of the new design for a liquid and cup dispenser having the removable bottom cover in place;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof;

FIG. 8 is an exploded view of the liquid and cup dispenser shown in FIG. 1;

FIG. 9 is a perspective side view of a golf cart showing the dispenser installed in place for transport;

FIG. 10 is a perspective view of the new design for liquid and cup dispenser having the bottom cover removed;

FIG. 11 is a front view of FIG. 10;

FIG. 12 is a back view of FIG. 10;

FIG. 13 is a first side view of FIG. 10;

FIG. 14 is a second side view of FIG. 10;

FIG. 15 is a top view of FIG. 10;

FIG. 16 is a bottom view of FIG. 10; and,

FIG. 17 is a rear perspective view of a golf cart showing the dispenser installed in place and ready for use.

The portions of the liquid and cup dispenser shown in broken lines form no part of the claimed design. The broken line showing of a golf cart in FIGS. 9 and 17 depicts environmental subject matter and forms no part of the claimed design.

1 Claim, 17 Drawing Sheets
